UNITED STATES PATENT OFFICE.

OLIVER S. GARRETSON, OF BUFFALO, NEW YORK.

SCHOOL-FURNITURE.

SPECIFICATION forming part of Letters Patent No. 246,670, dated September 6, 1881.

Application filed April 19, 1881. (No model.)

To all whom it may concern:

Be it known that I, OLIVER S. GARRETSON, of the city of Buffalo, in the county of Erie and State of New York, have invented new and useful Improvements in School-Furniture, 5 of which the following is a specification, reference being had to the accompanying drawings.

This invention relates to an improved construction of school desks and seats, and has 10 for its object to simplify the means whereby the wooden slats are secured to the iron frames, and to render the hinged seats easy and noiseless in their operation.

My invention consists of the particular construction of the means whereby the wooden 15 slats are secured to the iron frames, and of the construction of the hinges whereby the folding seats are attached to the stationary standards, as hereinafter fully set forth.

20 In the accompanying drawings, Figure 1 is a fragmentary sectional elevation of a school-seat provided with my improvements. Fig. 2 is an inside elevation of the knuckle formed at the inner end of the seat arm or iron. Fig. 3 is 25 an inside elevation of the knuckle formed on the standard, and to which the seat-arm is hinged. Fig. 4 is an outside elevation of the same knuckle. Fig. 5 is a section through the seat-hinge in line $x-x$, Fig. 1. Fig. 6 is a similar section, on an enlarged scale, in line $y-y$, Fig. 1. Fig. 7 is a reverse view of the plate which covers the inner side of the hinge. Figs. 30 8 and 9 are reverse and front views of the washer which is interposed between the covering-plate and the knuckle of the standard. Fig. 10 is a cross-section, on an enlarged scale, 35 of the seat-iron, slat, and means whereby these parts are secured together. Fig. 11 is a similar view, showing a modified construction of the fastening.

40 Like letters of reference refer to like parts in the several figures.

A represents the slats or wooden portions of which the seat is composed.

45 B represents the arm to which the slats A are secured; and D represents a portion of the standard or stationary frame of the desk. The slats A are constructed with a dovetail or undercut groove, a , and the seat-arm B is provided with a rib, b , which is placed in the groove a and fits against one side thereof, leaving an

open space between the opposite side of the groove and the rib a .

C represents a clamping-dog, which projects with its head into the open space between the 55 rib b and the undercut side of the groove a , and secures the rib b in the groove a . As shown in Fig. 10, the face of the dog C fits against the inclined side of the dovetail groove, and the back of the dog is made convex and 60 fits in a concave depression, c , in the side of the rib b . The outer end of the dog C is secured to the seat-arm by a screw-bolt, d , the nut of which is held against turning in a depression on the outer side of the dog. After 65 the rib b is inserted in the slot a , the head of the dog C is inserted into the open space between the rib and the side of the slot, when by applying the screw-bolt d the outer end of the dog is drawn against the seat-arm B and the 70 head of the dog pressed against the side of the groove, whereby the rib b is firmly pressed against the opposite side of the groove a , and the parts are firmly secured together. In the modification represented in Fig. 11, both the 75 face and the back of the head of the dog C are made convex, and the shank is arranged at right angles to the head and secured by a screw to the slats A, whereby the rib b is similarly secured in the groove a . I prefer, however, 80 the construction shown in Fig. 10, as it is more efficient. A number of these clamping-dogs C are arranged at suitable distances apart on the seat-arm or other part which is to be connected with the slat or other wooden portion 85 of the seat or desk. This fastening is readily applied and released at desire, and forms a very strong and durable means for securing the parts together.

E represents the knuckle formed on the 90 standard D, and forming part of the seat-hinge. It is provided with two peripheral bearing-surfaces, $e-e'$, arranged on opposite sides of the center of the knuckle, and having unequal radii, whereby two shoulders, $f-f'$, are formed 95 on the knuckle.

g is a circular concave depression formed on the inner side of the knuckle E, around the central opening, h , through which the fastening-bolt h' passes.

I represents the knuckle formed on the seat-arm, and provided with a curved recess, i ,

which surrounds the larger peripheral bearing-surface of the knuckle E, and terminates in two shoulders, $j'j$, which come in contact with the shoulders $f'f$ of the knuckle E when the seat 5 is down.

$k'k$ are two lugs formed on the inner side of the disk of the knuckle I, and projecting into curved recesses $l'l$, formed in the outer side of the knuckle E. The ends of these recesses are 10 provided with strips or blocks of rubber or other elastic material, against which the lugs $k'k$ strike before the shoulders $j'j$ and $f'f$ come in contact when the seat is lowered and before the seat reaches its highest position 15 when it is raised, thereby preventing noise.

L represents a convex washer, which is placed against the concave recess g of the knuckle E, and M is the covering-plate, which is placed over the washer L. The washer L is provided 20 with two ears, l^2 , which fit in recesses m in the plate M, whereby the washer L is compelled to move with the plate M. The recesses m are made sufficiently deep to permit rubber blocks n or other springs to be placed therein 25 between the ears l^2 of the washer L and the plate M, whereby the washer is pressed against the knuckle E and at the same time permitted to yield. The plate M is provided with two ears, o , which project beyond the peripheral bearing-surfaces of the knuckle E, and are connected with the knuckle I by studs or projections p entering sockets p' in the knuckle I, whereby the plate M is compelled to move with the knuckle I. In swinging the seat on its 5 hinge the convex washer L forms a bearing-surface, by which the movable knuckle works on the stationary knuckle, and it further serves to center the parts, thereby preventing the

peripheral bearing-surfaces from grinding upon each other. In this manner the friction 40 produced between the movable parts of the hinge is greatly reduced, and an easy noiselessly-working hinge is produced.

I claim as my invention—

1. The combination, with the slat or other 45 wooden part A, provided with a dovetail or undercut groove, a , of a seat-arm or other frame, B, provided with a rib, b , which fits against one side of the groove a , and is provided on its opposite side with concave de- 50 pressions and clamping-jaws C, seated in said depressions and projecting into the open space between the rib b and the side of the groove a , and secured by screw-bolts d , substantially as set forth.

2. The combination, with the standard- 55 knuckle E, provided with a circular recess, g , of the seat-knuckle I, washer L, projecting into the recess g , a covering-plate, M, attached to the seat-knuckle, and one or more springs in- 60 terposed between the covering-plate and the washer, substantially as set forth.

3. The combination, with the standard- 65 knuckle E, provided with a circular recess, g , of the seat-knuckle I, washer L, projecting into the recess g and provided with ears l^2 , the cov- 70 ering-plate M, attached to the seat-knuckle and provided with recesses m , and springs n , ar- ranged in the recesses m and bearing against the ears of the washer, substantially as set forth.

O. S. GARRETSON.
